RADIAL CYLINDER ROTARY COMPRESSOR
OR MOTOR

Guido Tacconi, Florence, Italy

Application July 29, 1952, Serial No. 301,470

Claims priority, application Italy January 29, 1952

2 Claims. (Cl. 103—161)

The present invention relates primarily to a rotational unit for the actuation of a plurality of variable volume chambers, this unit being composed of a plurality of radial cylinders located in a rotating block, the respective pistons for the cylinders being driven by connecting rods positioned in an additional member rotating around a geometrical axis parallel to and displaced with respect to the cylinder block axis, this block and this member are engaged by means of connecting rods or crankshafts. The timing of the cylinders is obtained in the center by means of a conical member capable of small axial displacements with respect to the seat located in the center of the cylinder block, so as automatically to adjust the seat along the conical surfaces, always keeping substantially constant the moment of friction, imparted to said conical member. The abovementioned automatism is attained by means of rollers and sloped surfaces co-acting between a stationary member and the conical one, in order to bring about the axial displacements of the latter, dependent upon the moment of friction, which tends to rotate the conical member. Passages or ducts for the feed and exhaust, extend along predetermined arcs, are in correspondence with the passages located in the cylindrical block for the cylinder heads, and are provided in the conical member.

The specified unit may act either as a working machine (compressor, pump) or as an endothermic or exothermic driving machine.

A particularly advantageous use for the unit is for the actuation of an exothermic machine, characterized by the fact that it comprises, positioned upon the same axis, the respective rotational shafts of at least one unit, as above described, and a compressor, advantageously made up of another of these same units, mutually coupled and provided with suitably different relative displacements, the first being designed to constitute the driving machine and the second to constitute a compressor for a fluid operating in a closed cycle. A coolant and a heat supply are included in this closed cycle. In this way a circulation of the fluid, coming from the heat source designed for the drive of the engine, is established. This fluid is led to the cooler from the engine exhaust and is therefore picked up by the compressor, driven by the engine, so as to be compressed and to be sent back to the heat source, preferably including a heat exchanger. The residual mechanical energy is obtained from the same shaft of the two units, by actuating a heat transfer from the heat source to the cold portion, that is, by bringing about a reduction of the heat level.

This invention will best be understood from the following specification and the hereunto appended drawings, which show diagrammatically embodiments of this invention.

In the drawings:

Fig. 1 shows schematically an exothermic machine, comprising two coupled units;

Fig. 2 shows, in axial section, a radial cylinder unit;

Fig. 3 shows a cross section, taken on the line III—III of Fig. 2;

Fig. 4 shows a longitudinal section of the conical member of the timing gear;

Figs. 5 and 6 are sections, taken on the lines V—V and VI—VI of Fig. 4, respectively.

2

As seen in Figs. 2 to 6, a unit according to the invention comprises a multiple-piece casing 1, extending with two axially removed sleeves 2—2a and 3—3a respectively, that is with parallel but offset geometrical axes of symmetry. The sleeve 3—3a is provided with flanges designed to form seats for two bearings 4 and 5, on which the shaft 6 is mounted. On this shaft, there is a seal unit, generally designed as 8, divided into two portions by a gearwheel 9, coaxial with the shaft 6, and which suitably forms a part of a lubricant gear pump, for instance, the second gear 10 of which is driven by a gearwheel 11, controlled by the shaft 6. This shaft 6 carries, at the inner end, in the casing 1, a disc 12, peripherally provided with a cylindrical longitudinal portion 12a projecting into the casing 1.

In the sleeve 2 there are the seats for two bearings 13—14, which are axially offset with respect to the axis of the shaft 6 and the bearings 4 and 5. A hollow shaft 15 is mounted on these bearings 13 and 14 and is provided with a flange, at the inner end within the casing 1. The cylinder block 16 is secured to the flange and thus is housed in the casing 1. Six cylinders 17, in which as many respective pistons 18 slide, are located in said block 16 in this embodiment. These pistons 18 are provided with connecting rods 19, which are engaged by pins 20, mounted at mutually equidistant positions on flanges 12b projecting inwardly from the cylindrical portion 12a of the disc 12, mounted on the shaft 6. On the disc 12 three connecting rods or goose-necks 22 are furthermore pivoted at 21. The end of the respective rods 22 are engaged by pins 23 in corresponding seats, located in the block 16; the connecting rods or goose-necks 22 have a distance between the centers equal to the displacement of the axes between the shaft's axis 6 (around which the disc 12 rotates) and the disc's axis 15, around which the block 16 rotates.

The block 16 centrally contains a cavity, wherein there is a member 24, which forms a frusto-conical seat (also see Fig. 4). The openings 25 for communication with the cylinder heads 17 lead into this frusto-conical seat. A conical member 26 is housed in this frusto-conical seat, formed by the element 24. This conical member 26 is made slidable on two portions, of different diameter, 27a and 28 of a shaft 27, coaxial with the shaft 15, stationarily mounted on the end block 2a of the sleeve 2. The difference of diameter between 27 and 28 creates, in the inside of the conical member 26, a chamber 29, wherein a spring 30 is housed. This spring 30, reacting on the shoulder between 27a and 28, tends to push the conical member 26 towards the left side with respect to Figs. 2 and 4, that is, towards the conical seat. A sleeve 31, adjustable as to the axial position thereof and carrying two rollers 32, having axes perpendicular to that of the shaft 28, is mounted on said stationary shaft 28. These rollers 32 register with two V-shaped indentations 33, located on the end edge of the smaller base of the conical member 26. An opening 34 extending between the conical surface (at the height of the openings 25) up to the inner chamber 29, is suitably located in the frusto-conical member 26. The inner chamber 29 is in communication, through holes 35, with the inner cavity of the stationary shaft 27. Furthermore a groove 36 (always in registry with the openings 25) is formed in the conical member 26 and is extended along a predetermined arc on the conical surface. The groove 36 is in communication through a plurality of holes 37 with the gap 38 resulting between the stationary shaft 27 and the hollow one 15, this gap being in communication with an outwardly directed duct 39.

The other elements of the device include suitable lubricating circuits, collecting means of the same, pick-up ducts

for leakage of fluid into the casing 1 and other necessary minor items.

The operation of the unit is as follows, referring to its utilization as a compressor. The fluid to be compressed is fed in through the duct 39 and reaches the groove 36, from which the fluid is sucked into the cylinders by the motion of the pistons, which—by the rotation of the unit according to the arrow shown in Fig. 3—are radially brought away, with respect to the cylinder block, from the lower position to the upper one. This is brought about by the effect of the displacement of the axes between the rotational axis of the block 16 and the rotational axis of the disc 12, carrying the pins 20. Along the downward passage (see Fig. 3) of the pistons, these, always due to the effect of the axial offset, compress the fluid in the corresponding cylinders, exhausting it through the opening 34 into the chamber 29 and then through the holes 35 into the inner cavity of the hollow shaft 27, which constitutes the delivery duct. The shaft 6 in this case operates a driving shaft, pulling the block 16 by means of the connecting rods or goose-necks 22.

When the unit operates as an engine, through a few appropriate changes of the amplitude of the groove 36 of the opening 34 and in the actuation of the timing in general, the driving pressurized fluid is led from the duct made up of the hollow shaft 27, enters into the cylinders through the opening 34, effecting a more or less prolonged expansion dependent upon the angular extension of the same opening 34 and then is exhausted through the groove 36 and the duct 39, the rotation in this case being opposite to that in the previous case.

In any event, the conical member 26, stressed by the spring 30, automatically adjusts, through its own slipping, the friction on the conical seat, always assuring a seal. In fact, when the friction between the conical surfaces increases for any reason, the rotating block 16 tends to rotate the conical member around the stationary shaft 27—28, but then the stationary rollers 32, owing to the V-sloped surfaces 33, bring about a slight sliding of the member 26 (towards the right side of the drawing) pulling it out of the seat 24 until the friction is brought back to the predetermined value. The spring 30 and the action of the pressures of the fluids on the member 26 are appropriately calculated and predetermined in order to obtain its balance.

A particularly advantageous application of the above described unit is as follows (see Fig. 1):

Two units, similar to those already described, and illustrated as M and C in Fig. 1, are coupled by means of shafts, corresponding to the shaft 6, a dynamo D or other machine (electrical or otherwise), is moreover designed to utilize the mechanical energy on the common shaft of the two units C and M, and is integral with the shaft. The unit M, having the higher total capacity, is designed to constitute the driving engine of the system and is supplied through the piping 51, leading from a heated fluid source, made up more especially of a heat exchanger S; the exhaust of the engine M is carried through a duct 52 which leads to a cooler R where the fluid is cooled and then decreased in its volume and eventually condensed. From the cooler R, the fluid passing through the duct 53 arrives at the unit C, operating as a compressor, which impells the fluid into the duct 54 feeding the heat exchanger, which also is the same element as the source S, with the fluid.

The mechanical energy delivered by the driving engine M, utilizing the lowering of the heat level from S to R, is designed partially to drive the unit M—C, while the residual portion may be utilized by the machine D, for instance, made up of a dynamo or the like.

The above described embodiment may also be used when the differential of level of heat between the two sources S and R is restricted and may be brought about by also providing a heat accumulator in the circuit, designed to store the heat picked up from any suitable source

and then returned during the operation of the closed cycle exothermic engine above described. As a source of heat, for instance, it is possible to use the sensitive heat at the exhaust of a burner, of a furnace, a boiler, a fireplace or other. The cooling action may be accomplished by the use of a normal temperature water circulation heat exchanger or the like. The fluid, which acts in the closed cycle, may be made up of air, steam or low temperature volatile liquids, such as ether, ammonia, carbon dioxide or any other substance in a gaseous phase or in a liquid and gaseous phase. In this case, the compressor C may be constituted by a unit as above described, or it may be a simple gear pump or the like. A suitable device designed to start the rotation of the moving members, if and when the pressure of the operating fluid is restricted, in order to overcome the coefficient of friction of a state of rest, may be provided.

The described unit being reversible and thus being in condition as to operate as an engine or as a compressor, may also be used for the actuation of an endothermic cycle, introducing heat, by means of a burner, in the air or any other compressed fluid, which is injected by the compressor into the engine and is exhausted to the outside air.

While certain embodiments of this invention have been shown and described, by way of example, the scope of this invention is limited only by the hereunto appended claims.

What I claim is:

1. A radial cylinder rotational unit, including a rotating block, a plurality of cylinders located in said rotating block, pistons sliding in said cylinders and connecting rods controlling said pistons, another element rotating upon an axis parallel and displaced with respect to that of the rotating cylinder block, the driving connecting rods of said pistons being engaged with said additional rotating element, small connecting rods mutually engaging said rotating cylinder block and said second rotating element, in said assembly, timing elements including a conical member, a conical seat located in said rotating cylinder block housing said member and provided with communicating apertures towards the cylinders, a stationary shaft coaxial with said rotating cylinder block and whereon said conical member is slidably fitted, rolling members carried by one of said timing elements, sloping surfaces engaging said rolling elements and carried by another one of said timing elements, a resilient member interposed between said stationary shaft and said conical member and coacting with said rolling members in order to determine the axial displacements of the latter according to the moment of friction transmitted by the conical seat to the conical member and which tends to rotate said conical member, feed and exhaust passages located in said conical member and cooperating with said communicating apertures of the cylinders.

2. A radial cylinder rotation unit, according to claim 1, wherein a ring is engaged to said stationary shaft and carries the rollers, and wherein a threaded nut is screwed on to said stationary shaft, in order to adjust the axial position of said ring.
